UNITED STATES PATENT OFFICE.

CHESTER E. HENING, OF NORTH BALTIMORE, OHIO.

RAIN-WATER FILTER.

SPECIFICATION forming part of Letters Patent No. 788,102, dated April 25, 1905.

Application filed December 21, 1904. Serial No. 237,760.

To all whom it may concern:

Be it known that I, CHESTER E. HENING, of North Baltimore, county of Wood, and State of Ohio, have invented certain new and useful 5 Improvements in Rain-Water Filters; and I do hereby declare that the following is a full, clear, and exact description of the invention, which will enable others skilled in the art to which it appertains to make and use the same, o reference being had to the accompanying drawings, and to the figures of reference marked thereon, which form part of this specification.

This invention has reference to a rain-water filter; and it has for its object to provide an 5 improved device of this character for effectively removing the usual foreign material—leaves, twigs, insects, soot, &c.—carried by water from the roof of a building into the cistern.

o A further object consists in arranging the parts within the filter-casing so that they may be readily removed therefrom for the purpose of cleaning.

In carrying out my invention I employ the 5 novel combination and the arrangement of the parts hereinafter shown, described, and claimed.

In the accompanying drawings, Figure 1 is a view showing my filter. Fig. 2 is a trans- 5 verse section thereof, illustrating its operation. Figs. 3 and 4, respectively, are perspective views of the filter parts removed from the casing.

Referring to the drawings, 1 is a sheet- 5 metal casing of rectangular shape adapted to be secured in any suitable manner to the side of a building, the same being provided with a removable cover 2, the inlet for water from the roof being indicated at 3 and the outlet or o discharge to the cistern at 4.

5 is a sheet-metal slide or partition removably secured in the casing, the same extending crosswise in a vertical plane between the front and rear walls thereof, the casing being divided thereby into two chambers 6 and 7, passage from the chamber 6 into the chamber 7 being effected through a plurality of transversely-arranged perforations 8 near the upper end of the partition. The partition is guided upon insertion and removal between

flanged pieces 9, secured one to the front and the other to the rear wall of the casing.

10 is a pocket carried by the partition 5, adapted to contain pieces of sponge or like filtering material, (indicated at 11,) one side of 55 the pocket being formed by the perforated portion of the partition, the other side, 12, being a section of wire screen soldered at its upper and lower margin to the partition.

13 is a basket, of reticulated material, the 60 same having a rectangular shape to completely occupy the lower end of the chamber 7. This basket is also permanently carried by the slide 5, being removed from the casing when the slide is removed therefrom. 65 Within the basket 13 is placed a quantity of loose charcoal, the same serving as a filtering and purifying agent for the water.

14 indicates an elongated rectangular screen having a suitable marginal frame 15, of metal, 70 imparting stiffness and rigidity thereto. At its lower end the screen is turned upwardly, as at 16, providing a pocket for the reception of foreign material deflected into the same from the face of the screen. As shown in 75 Fig. 2, the screen 14 is inclined steeply within the chamber 6, with its upper margin resting upon the slide 5, the same being capable of ready removal from the casing when desired.

80 17 is a cock at the bottom of the chamber 6, adapted to drain any accumulated sediment therefrom.

The operation of the filter is as follows: The water entering the filter-casing at 3 is discharged directly into the water contained in the chamber 6, the force of the discharge being broken before it reaches the screen 14, which, it is observed, is submerged in the chamber 6. It is apparent that if the screen 14 85 were not submerged the usual foreign material contained in rain-water—decayed leaves, twigs, insects, &c.—would be forcibly directed against the same, the force of the impact, aided by the action of the water, reducing the 95 foreign material to extremely fine particles capable of readily passing through the screen. The disintegration of the foreign material is entirely prevented by the arrangement of screen shown. The foreign material after 100

being discharged into the water within the chamber 6 is carried without undue violence against the inclined screen, being then deflected into the pocket at the lower end of the 5 screen out of the path of the current. (Indicated by the arrows, Fig. 2.) The coarser foreign material having been removed from the water there still remains therein the finer material, such as soot and dirt, held in mechanical suspension. This finer material is removed by the sponges contained in the pocket carried by the slide, the water passing through the perforations in the slide. The charcoal in the basket at the lower end of the 10 chamber 7 accomplishes the final removal of all foreign material, the water being discharged into a cistern or other suitable receptacle.

One of the features of my invention lies in 15 the facility with which it may be cleaned. Since the coarser foreign material is deposited in the pocket at the lower end of the screen 14, the same is readily removed from the casing by lifting the screen out of the chamber 6. Any sediment or deposit of fine material 20 at the bottom of the chamber 6 may be readily discharged by opening the cock 17. The removal of the slide 5 carries with it the sponge-pocket and also the receptacle for char- 25 coal, these parts being cleaned by thorough drenching with water. It will be observed 30 that when the screen and the slide are removed from the casing the latter is simply a rectangular box-like structure, the water being 35 free to pass therethrough without obstruction. This is desirable in winter, the parts being removed to prevent their freezing when the weather conditions would indicate 40 a sudden drop in the temperature.

The improved operation of my invention 45 will be apparent.

Having described my invention, what I claim, and desire to secure by Letters Patent, is—

1. A rain-water filter comprising a casing, a partition dividing the casing into two chambers and provided with passages for water, a

structure containing a filtering medium disposed in one of the chambers, an inclined screen submerged in the other chamber, an upturned portion forming a pocket at the lower end of said screen, a water-inlet at the top of the chamber containing the submerged screen, and an outlet at the bottom of the other chamber, substantially as described. 55

2. A rain-water filter comprising a casing, a removable partition provided with passages for water through its upper portion, said partition dividing the casing into two chambers, an inlet for water at the top of one of the 60 chambers, an outlet at the bottom of the other chamber, an inclined screen submerged in the chamber having the water-inlet and removably seated in said chamber, said screen having an upturned lower portion, and a reticulated structure containing filtering material carried by the removable partition and disposed within the chamber provided with the water-outlet, substantially as described. 65

3. In a rain-water filter, a casing, a partition dividing the casing into two chambers, slidably secured between its front and rear walls, said partition having passages through its upper portion, a pocket containing filtering material arranged in front of said passages, a reticulated basket containing filtering material carried by said partition and occupying the lower portion of the chamber on one side of the partition, an inclined screen provided with an upturned lower portion submerged in the chamber on the other side of said partition, said screen being removably seated in said chamber, an inlet leading into the top of the chamber containing the inclined screen, and an outlet at the bottom of the 70 other chamber below the reticulated basket, substantially as described. 75

In testimony that I claim the foregoing as my own I affix my signature in presence of two witnesses.

CHESTER E. HENING.
